VACUUM CLEANER PNEUMATIC ANNUNCIATOR

Filed July 11, 1938

UNITED STATES PATENT OFFICE

2,270,318

VACUUM CLEANER PNEUMATIC
ANNUNCIATORWard Leathers, Haworth, N. J., assignor to
Quadrex Corporation, New York, N. Y., a cor-
poration of Delaware

Application July 11, 1938, Serial No. 218,647

1 Claim. (CL 116—67)

My invention applies particularly to canister type vacuum-cleaners, i. e., those having the filter enclosed in a casing along with a motor-driven air-impelling unit.

This type of vacuum-cleaner has its air flow easily impeded by the accumulation of dirt, such as carpet nap, on the walls of the filter, and where the filter is designed of such type that it may be shaken, it is highly desirable to know when such shaking should be done, particularly when the air flow is obstructed to the point where the cleaning function at the nozzle is materially impaired, although the cleaner has not accumulated sufficient dirt to require emptying.

The object of my invention is to produce an automatic device that will inform the operator audibly of the true working condition of the machine. It is the object to give a mild notification of the fact that the nozzle is not cleaning at its full capacity, to give a more strident notification if the cleaning function becomes still more seriously impaired, and to give an insistent and vociferous indication if a careless operator permits the dirt to accumulate in the filter, or the dirt-receptacle, or both, to a point where the machine is practically useless for cleaning purposes.

Machines of the type described usually have within the case areas or chambers of several different pressures when the machine is in operation. This invention functions by means of these several pressures. First, there is the pressure within the filter, which, theoretically at least, would be atmosphere resisted only by the nozzle and the impedance to flow through extension tube and hose; this pressure is normally below atmosphere. Second, there is a still lower pressure, the lowest in the machine, between the filter and the air compressor (heretofore called the motor-driven air-impelling unit). Third, there is a pressure in the area of the machine after expulsion of air from the compressor and before it has passed to the open air, which is normally higher than atmosphere.

My invention is concerned with determining the resistance to air flow through the filter which alters the normal difference between the first and second named pressures; and it utilizes the third pressure (or atmosphere could be substituted) for annunciating purposes when actuated by means controllable by the differential pressure between the first two pressures. Such a device gives information concerning the accumulation of dirt on the surface of the filter, and its resistance to air-flow therethrough, as ex-

pressed in terms of differential pressures and, as disclosed in this specification, gives an annunciation relative to the amplitude of said differential and hence of said resistance.

5 My invention is applicable to canister type vacuum-cleaners of the horizontal-axis type or the vertical-axis type, but I have preferred to set it forth as applied to a vertical-axis type machine. (A more complete description of the 10 type shown herein may be found in my co-pending application for Letters Patent, Serial No. 209,909.)

In order to set forth my invention so that all those familiar with these arts may understand 15 it, I have prepared the following specification, to which I have appended the drawing, of which:

Figure 1 is a vertical, partial cross-section of a vertical-axis type canister vacuum-cleaner incorporating this invention.

20 Figure 2 is a vertical cross-section of the annunciator.

Figure 3 is a vertical cross-section of a modified sound producer for same.

25 Figure 4 is a vertical cross-section of a pressure-juncture for the filter.

Figures 5 and 6 show the filter shaking mechanism.

A vertical-axis canister type vacuum-cleaner with an upper portion 1, Fig. 1, comprising a 30 filter 2, a motor-driven air-impelling unit 3, an exhaust pressure chamber 4, sound muffler (or supplementary filter) 5, and handle 6, is separable from a lower portion 7 comprising a dirt-receptacle pan 8 and a hose attachment 9 along 35 a horizontal line, indicated at 10. A filter 2 comprises two truncated cones joined together at a ring 11. The ring is movable in all directions for shaking purposes by a handle 12 on the outside of the machine. This handle mechanism is hingeable and raisable, passes into the machine through rubber washers 13 (see Fig. 5) so that it has a substantially universal movement. The filter ring 11 is held up by springs (shown in Fig. 6). A stop 14 on the handle enables the ring to be depressed for shaking purposes by means of a bow 15 operably related 45 with the handle and joined by means of trunnions to the sides of the ring 11. The filter 2 requires no fastening at its center 16 where it is drawn by the springs mentioned, over a supporting nose 17 (more fully shown in Fig. 4).

Air entering at the hose juncture 9 passes upward into chamber 18 within the filter. It then passes through the filter to a chamber 20 from which it is drawn by the fan 21 through an inlet

to the fan 22. The filter is spaced from the inlet 22 by means of any desirable spacer 25, such as a wire cage. The air from the fan 21 is delivered to chamber 4 from whence it finds exhaust to atmosphere through muffler or auxiliary filter 5. During this operation the pressures within the three chambers mentioned differ widely. That within the chamber 20 is the lowest, being considerably below atmosphere. That within the chamber 18 is not so low as that in chamber 20 but also below atmosphere. That within the chamber 4 is above atmosphere. The differential pressure between the inside filter-chamber 18, and the suction chamber 20 varies in use. As dirt accumulates on the filter the machine becomes less efficient. It is desirable under these circumstances to notify the user who may then shake the filter and renew the full efficiency of the machine. If, however, the filter and dirt-receptacle accumulate such quantity of dirt as to continuously impair the cleaning function, it is desirable that the operator be notified of that fact so that the machine must then be emptied. I have accomplished this purpose by means of a sound device illustrated in Fig. 2. An annular diaphragm 30 is enclosed on both sides forming a lower pressure chamber 31 which communicates by means of a hollow wire 32 with the chamber 18 within the filter. This means of communication may be established in any desired manner, but for the type of machine set forth herewith the method is described under Fig. 4. An upper pressure chamber 33 communicates by means of a tube or hose 34 with the middle chamber 20. In the upper diaphragm enclosure I have provided a valve 35, the stem of which is joined to the diaphragm 30. When the valve is raised by pressure beneath the diaphragm the valve 35 uncovers ports which permits air from the high pressure chamber 4 to pass into the chamber 33 and on into the chamber 20 by means of the tube 34. This movement of air is utilized for making sound in any desired manner. By enclosing the inlet, as at 40, and properly disposing a reed 41, such as is used in saxophones or other wind instruments, sound is produced when the valve is opened. The diaphragm is shown as an annular, corrugated, bronze sheet having its own spring resistance to displacement. It may, of course, be provided with a spring (Fig. 3), if desired, to resist its upward move-

ment. A bracket 43 is used for holding this diaphragm-pressure-unit to the top of the machine. As the differential between the pressures in chambers 18 and 20 increases, the valve 35 tends to open more and more. As the opening increases the sound produced by the reed 41 increases in volume. By predetermining the spring resistance, the reed may be made to give a modest note when the cleaning at the end of the nozzle becomes somewhat impaired. It may be made to produce an ever louder note or sound with the increased impairment of the cleaning function. It should be noted for the purpose of operating this sound device that air from the chamber having the highest pressure in the machine is permitted to pass to the chamber having the lowest pressure in the machine.

Any other sound device operated by pressure-air may be used. As an illustration, a diagrammatic whistle is shown in Fig. 3. Air passing through the openings 45 and 46 produce sound in volume roughly proportionate to the air-flow.

The separator cage 25, see Fig. 4, is provided with inner and outer ferrules 48 between which the wires are joined. An inverted moulded rubber mushroom 50 is held within the inner ferrule. The hollow wire 32 is joined to the top of the rubber mushroom and communicates by means of a hole through the rubber with an open chamber 51 at the bottom. Air pressure within the filter communicates through the filter to the chamber 51, hence to the inside of the hollow wire registering the pressure of the chamber 18 on the lower side of the diaphragm.

Having set forth my invention in understandable terms, I wish to make note of the fact that many types of sound devices operated by air may be used and controlled by the differential pressures as set forth in this specification without departing from the spirit of my invention.

What I claim is:

In an audible indicator for use on a vacuum-cleaner, a sound-producing device operated by air supplied by the differential in pressure between the inlet and outlet sides of the air impeller of said cleaner and having means responsive to a second pressure differential, that on opposite sides of the filter of said cleaner for controlling the flow of air through the said sound-producing device.
